UNITED STATES PATENT OFFICE.

FRANK D. POWELL, OF BOSTON, MASSACHUSETTS, ASSIGNOR TO THE LAMSON COMPANY, OF BOSTON, MASSACHUSETTS, A CORPORATION OF NEW JERSEY.

UPSEND WIRE-LINE CARRIER.

1,213,006.

Specification of Letters Patent.

Patented Jan. 16, 1917.

Application filed December 4, 1913. Serial No. 804,763.

To all whom it may concern:

Be it known that I, FRANK D. POWELL, a citizen of the United States, residing at Boston, in the county of Suffolk and State of Massachusetts, have invented certain new and useful Improvements in Upsend Wire-Line Carriers, of which the following is a specification.

This invention relates to wire line carriers and more especially to what I have termed an up-send carrier apparatus.

In stores, for example, where apparatus of this description may be installed it will be possible to serve an upper floor with carriers from a main or lower floor cash desk; and it is one of the objects of the present invention to provide a combination of elements including a wire-line track, or its equivalent, adapted to efficiently accomplish this purpose.

The service in question may be at right angles to the main or lower wire line and the sub or clerk-station served may be at a level considerably above the sending or desk-station. For example, it has been found practicable to transmit carriers by apparatus of the type hereinafter more particularly described, over a line 78 feet long with an 8 foot rise to the upper or top station.

A further and important object of my invention has been to provide novel means in apparatus of the type in question, for retaining the carriers at the upper station; which means while not preventing or even materially impeding intentional despatch of carriers from said station is nevertheless adapted to effectively prevent an inadvertent release or despatch of the carrier.

These and other objects of my invention will be hereinafter more especially referred to and the novel elements and combinations of elements whereby said objects may be attained will be more particularly pointed out in the claims appended hereto.

In the drawing which forms a part hereof and in which like reference characters designate like parts throughout the several views, I have exemplified a preferred embodiment of my invention; but as I am aware that various changes and modifications may be made herein without departing from the spirit of my invention, I desire to be limited only by the scope of said claims

broadly considered in the light of my disclosure.

Referring to the drawing, Figure 1 is a side elevation of an up-send wire line apparatus. Fig. 2 is a section taken on line II—II of Fig. 1. Fig. 3 is a detail of the carrier latching mechanism disposed at the upper station, a carrier being in place therein. Fig. 4 is a fragmentary plan view of a portion of a suitable propelling device. Fig. 5 is a section of Fig. 1 taken on line V—V showing the forward end of said propelling device. Fig. 6 is a detail section of a portion of the track taken on line VI—VI of Fig. 1. Fig. 7 is a detail section taken on line VII—VII of Fig. 1. Fig. 8 is a detail section taken on line VIII—VIII of Fig. 2. Fig. 9 is a detail of a pulley block shown in Fig. 1, and Fig. 10 is a detail of a fragment of the track at the upper station, showing a friction piece or tube thereon; the fragment being viewed from the line X—X in Fig. 1.

In so far as the construction of the lower station, broadly designated 1, is concerned, it may be of any suitable description adapted to effectively propel the carrier broadly designated 2 along the track 3 toward and up to station 4.

In the present instance station 1 comprises the usual hanger 5 and its bracket 6 pivotally or otherwise connected to the end 85 of the hanger and serving as a support for the lower end of the track 3.

The station may be provided with the usual handle 7 connected to the propelling cord 8 which in turn may be connected to a frame 9, guidedly movable upon rods 10 and the forward extremity of which is provided with a cross-head 11 to which are connected the extremities of a cord 12 which extend forwardly therefrom around pulleys 13, back 95 to the respective pulleys 14 mounted on said head; said cords thence extending forwardly again and around pulleys 15 and finally rearwardly again to provide the usual carrier engaging loop 12'.

Pulleys or idlers 13 and 15 may be mounted upon a somewhat U shaped block 16 secured to the outer extremities of the rods 10.

When handle 7 is drawn down a short distance the spring 17 in the tubular portion of frame 9, which is normally compressed when the carrier is at the station, transmits the propelling impulse to the frame 9 to retract

the latter and owing to the disposition of the cord 12 and its several pulleys, the loop in said cord travels through a considerable distance and propels the carrier 2, then in 5 its dotted line position, outwardly along track 3.

Track 3 is preferably connected to bracket 6 through the intermediacy of a bumper block 6' which may be provided with the 10 usual pawl and ratchet 18 by means of which the track is given the desired tension.

Above the track 3 is disposed a taut wire 19 which may be correspondingly connected to bracket 6 through the intermediacy of the 15 pawl and ratchet 18' and ratchet block 21; this latter also serving conveniently to support the pulley or idler 22 around which passes the cord 8.

Suitably mounted, as by means of a 20 hanger 23 and brace 24, below the flooring or platform 25 of the station 4 is an arcuate track support 26, the cross section of which may be T shaped, as shown in Fig. 6. Riveted to the outer side of this support is a 25 strip or plate 27 of sheet metal or the like, disposed so as to expose one edge thereof; this edge being curled or bent around as at 27' to inclose the curved portion of the wire track so that at this portion the curled edge 30 of the strip actually provides the track surface upon which the carrier rides when passing around the bend leading up to station 4.

The hanger 23 and its brace 24 may be suitably connected to the support 26 by 35 means of brackets 28 and 29, the latter being preferably pivotally connected to the respective extremities of the hanger 23 and brace 24 as indicated in Figs. 1 and 2. The taut wire 19 also extends around and upwardly 40 adjacent to the support 26 and may be connected thereto by bracket 30, passing thence around by a series of abrupt bends to successively engage portions 31 of the brackets 28 and 29, which are adapted to receive said 45 wire 19; then through bracket 32, and up to the cap or frame 33 which is supported upon uprights 34 at the station 4. Track 3 after 50 it emerges from the curled edge of strip 27 passes upwardly and is attached to a bumper block 35 which in turn is pivotally connected to the frame 33, above referred to.

About the upper end of the wire track, adjacent the bumper 35, is a friction tube 36, the function of which is to check an upwardly moving car by engaging the friction block 37 commonly provided upon cars of 55 this description. It will be understood, of course, that other means may be employed to arrest the upwardly moving carrier but I 60 prefer to use a type of car which is already upon the market. The friction tube also contacts with the block 37 to prevent the carrier, when at station 4, from dropping too freely, and if the frictionally engaged parts be not 65 badly worn they will of themselves, usually

prevent the inadvertent re-despatch of the carrier from the station, by gravity. I prefer to provide more positive means for this purpose, however, which will be hereinafter described, the friction means of themselves 70 not being positive.

The carrier shown comprises the usual detachable cash box 2', wheels, etc.; the block 37 engaging one side of the tube or thickened track 36 and pressing it against the outer 75 pair of wheels by the action of its spring 37'. The lower end of tube 36 may be coned, as at 36', to enable the carrier to freely ride up thereupon, and a strip 38 is attached by a clip 39 to the lower extremity of said tube. 80 This strip may be conveniently fastened at its upper end to the frame 35 and serves as a support for the positive carrier retaining means above referred to. This means comprises a somewhat zig-zag shaped element 40 85 which has at its lower extremity a lip 41, preferably of fiber, adapted to engage the lower lug-shaped corner 42 of the carrier, to thereby latch the same against inadvertent downward movement. When these parts 90 are in such engagement the V-shaped middle portion 40' of the element 40 is disposed between the outer pair of wheels of the carrier, as shown in Fig. 3. The lip 41 normally is given a bias toward its carrier latching position, as for example, by means of a spring 43 which presses against the upper end of the element 40 and which is affixed to a bracket 44 secured to the strip 38, above referred to, at a convenient level. When a 100 carrier has been arrested in the position of that shown in Fig. 1 and the friction parts fail to hold it in such position, as by reason of vibration in the line wire, or from other cause, said carrier will gradually slide 105 downwardly until its first or forward outer wheel encounters the upper surface of the V-shaped part 40'. The element 40 will thereby be driven slowly outwardly until the said first wheel has cleared the V-shaped 110 part, whereupon the lip 41 will be moved inwardly toward the carrier, in the present instance, by the spring 43, into locking or latching engagement with the nose or corner 42. As a result, further downward movement 115 of the carrier is positively prevented but the carrier may be released for the purpose of despatching it to the lower station by merely raising it until its said lower wheel is again above or operatively engaged 120 with the part 40', when, if the carrier be driven downwardly with abruptness, or at a velocity in excess of a determined amount, its lower wheel will drive outwardly the latching element and its nose or element 42, 125 which is mounted to adapt it for reciprocatory movement, will clear the lip 41 before the latter has had an opportunity by reason of its inertia to swing back into its latching position. Thereafter the carrier will con- 130

tinue downwardly around the curved portion of the track and thence along the horizontal portion of the track 3 to station 1. At the latter station the momentum of the carrier is gradually checked as the loop 12' of the cord 12 is drawn toward the bracket 6; the frame 9 being correspondingly, but in such less degree, moved toward the cross head 16, thereby compressing the light spring 17, since the handle 7 will at such time be in engagement with the bracket 6. The friction block of the carrier will in the last portion of its movement engage a friction tube 45 and the carrier will come to rest against the bumper carried by the block 6'.
 5 10 15

To redespach the carrier to station 4 the handle 7 is pulled sharply downwardly whereupon the carrier will be drawn out of engagement with the friction tube 45 and will be projected along the track 3 with sufficient force to impel it upwardly around the curved track, on to the friction tube 36, so that it will normally come to rest substantially in the position in which it is shown in Fig. 1. The frame 9 will then be in its rearmost position, but the spring 17 will expand as soon as the handle 7 is released and will retract the latter substantially to its upper position. The latching device will offer no material resistance to the ascending carrier but will invariably arrest inadvertent downward movement thereof after the nose 42 of the carrier has cleared the lip 41, so that even if the carrier should not have been impelled with sufficient force to drive it up above the bracket 44, the carrier will be latched, if it be not frictionally held, if it shall only have moved upwardly but a short distance 20 25 30 35 40 upon the friction tube 36.

It will thus be seen that I have provided a very simple carrier latching mechanism which, while adapted to effectively hold a carrier at a station, is nevertheless adapted 45 to release the carrier merely by the action of grasping the carrier itself and moving it up before giving it a thrust in the direction in which it is to travel, if the carrier be in actual latching engagement, at its forward extremity, with the lip 41. Obviously if it be above the latch a sufficient distance to insure the proper lateral displacement of said lip by its forward wheel, it may be thrust directly downward for despach, without having to first elevate it.
 50 55

I particularly direct attention to the combination of elements present in the exemplified construction whereby in such preferred apparatus it is necessary to propel the carrier past a determined point in the track (i. e., that where the carrier front wheel clears or substantially clears the operating part 40' of the latching mechanism) at a velocity in excess of a determined amount 60 65 or speed; since otherwise the lip 41 will

have time to move back into its latching position. In other words the carrier, which when not being intentionally despached is constrained by the engagement of the friction pieces 36 and 37 to move, if it moves at all, in a determined manner or slowly down toward the lip 41 is nevertheless capable of being despached by being thrust rapidly downwardly by hand through a short path, the length of which is from the said determined point to the point at which the forward end of the carrier can no longer be operatively engaged by the lip 41.
 70 75

The novel means for stiffening the wire track at the curve are of value in that they not only support the track at this point but prevent distortion thereof by the inertia of the rapidly moving carrier.
 80

Finally it will be noted that the carrier is laterally guided in its upper or down movements, while at the upper station, by the engagement of the guide rods 46 with the portion of the frame thereof which carries the cash receptacle 2'; since it is desirable to definitely position the carrier with respect to the latch at the upper station and this disposition of the guides permits of the employment of carriers now in common use without necessitating any modification thereof.
 85 90 95

Having thus described my invention what I claim is:

1. In store service apparatus, the combination of a high level station and a low level station with a carrier, a track between said stations having an upwardly directed curve therein around which said carrier may travel, means for propelling said carrier along said track from the station at the lower level around said curve to the station 100 at the higher level, and means at the high level station for latching it against inadvertent downward displacement, said latching means having provisions for automatically releasing said carrier when the carrier itself 105 is alone engaged by the hand of the operator and actuated to despach the same.
 110

2. In store service apparatus, the combination of a station with a track, a carrier adapted to travel along said track, means 115 for locking said carrier against inadvertent despach from said station along said track, and co-acting means for rendering said locking means inoperative to retain said carrier, only when said carrier is propelled past a 120 determined point in said track at a velocity in excess of a determined amount.

3. In store service apparatus, the combination of a track with a carrier and means for holding said carrier against despach 125 along said track unless said carrier is propelled past a determined point in said track at a velocity in excess of a determined amount, said holding means having a carrier engaged part operative to free the car.
 130

rier engaging the same from the restraining action of said holding means, only when said carrier is propelled past said point in said track in manner aforesaid, said carrier being out of engagement with said part after it leaves said point in said track.

4. In store service apparatus, the combination of a track with a carrier and means for holding said carrier against despatch along said track unless said carrier is propelled past a determined point in said track at a velocity in excess of a determined amount, said holding means having an operating part adapted for engagement with said carrier before the latter reaches said point, said operating part having a bias for a determined position and being displaced from said position by the passing carrier.

20 5. In store service apparatus, the combination of a track with a carrier, and means for holding said carrier against movement along said track in a determined direction, when said carrier is in actual engagement with said holding means, until said carrier has first been moved in a direction opposite that aforesaid and thereafter driven in said determined direction at a speed in excess of a determined amount.

30 6. In store service apparatus, the combination of a track with a carrier, and means for holding said carrier against despatch along said track unless said carrier is propelled past a determined point in said track at a velocity in excess of a determined amount, said track being disposed to cause gravity to tend to despatch said carrier.

7. In store service apparatus, the combination of a track with a carrier, means for holding said carrier against despatch along said track unless said carrier is propelled past a determined point in said track at a velocity in excess of a determined amount, and provisions for normally preventing said carrier when moving toward said point, in a direction to despatch said carrier, from moving with a velocity as great as the determined velocity aforesaid.

50 8. In store service apparatus, the combination of a track with a carrier, means for holding said carrier against despatch along said track unless said carrier is propelled past a determined point in said track at a velocity in excess of a determined amount, and frictionally acting means for normally preventing said carrier when moving toward said point, in a direction to despatch said carrier, from moving with a velocity as great as the determined velocity aforesaid.

9. In store service apparatus, a track, a carrier to travel thereon, a latch for said carrier, and means to yieldingly support said latch to allow it to be swung sideways when said carrier is traveling in one

direction and to cause it to latch said carrier when it is traveling in a determined manner in the other direction, said latch supporting means having a carrier actuated part for preventing the latching of the carrier when traveling in said other direction in a manner other than that aforesaid.

10. In store service apparatus, a track, a carrier to travel thereon, a latch for said carrier, means to yieldingly support said latch to allow it to be swung sideways when said carrier is traveling in one direction and to cause it to latch said carrier when it is traveling in a determined manner in the other direction, and means for insuring that said carrier, if traveling at all in said other direction, shall travel in said determined manner except when being intentionally despatched along said track.

11. In store service apparatus, a track, a carrier to travel thereon, a latch for said carrier, and means to yieldingly support said latch to allow it to be swung sideways when said carrier is traveling in one direction and to cause it to latch said carrier when it is traveling in the other direction, said latch supporting means having provisions for releasing said carrier from the action thereof by a sudden thrust upon said carrier in the direction in which it is to travel and through a path of determined length in which, while traversing said path, said carrier is still subject to the latching action if its progress be stopped.

12. In a store service apparatus, an upwardly extending track, a carrier to travel thereon, a latching device near the upper end of said track beyond which, however, said carrier may travel, and separate means for checking the upward progress of the carrier, said latching device adapted to hold said carrier against inadvertent downward despatch.

13. In store service apparatus, a track leading downwardly from a station at a higher level to one at a lower level, a carrier adapted to travel along said track, and yielding means having a part adapted to engage said carrier to hold it at the upper station, said means having a second part adapted to be pressed aside by the carrier when the latter is thrust downwardly thereagainst, said second part being operatively connected to said first part to, at such time, move the latter to its carrier releasing position, and means at said lower station for propelling the carrier up past said first mentioned part.

14. In store service apparatus, a station, a wire track leading therefrom and curved in a portion thereof, a curved strip having a portion thereof bent around the curved portion of the track throughout substantially the length thereof, auxiliary means for stiffening both the wire track and said

strip at said curve, a carrier adapted to travel along said track around said curve, and means for propelling said carrier along said track.

- 5 15. In store service apparatus, a track leading down from an upper to a lower station, said track having a curve therein, a carrier provided with a receptacle and adapted to travel along said track, means for propelling said carrier from said lower station around said curve to said upper station, means for retaining said carrier at said upper station against the action of gravity, and guides for engaging said carrier upon 10 the receptacle side thereof to definitely position said carrier at the upper station, with respect to said curve.
- 10 15. In store service apparatus, the combination of a track with a carrier, and means for holding said carrier against movement along the track in a determined direction, said means having provisions to release said carrier by an engagement of a part of said carrier therewith, said part being other than 20 that which is directly held by said means when the carrier is held against movement in said determined direction.
- 20 25. In a store service apparatus, an up-

wardly extending track, a carrier to travel thereon, and a latching device near the upper end of said track beyond which, however, said entire carrier may travel, said latching device adapted to hold said carrier against inadvertent downward despatch.

18. In store service apparatus, the combination of a high level station and a low level station with a carrier, an upwardly extended track between said stations along which said carrier may travel, means for propelling said carrier along said track from the 35 station at the lower level to the station at the higher level, and means at the high level station for latching said carrier against inadvertent downward displacement, said latching means having provisions for automatically releasing said carrier when the carrier itself is alone engaged by the hand of the operator and actuated to despatch the same.

In testimony whereof I have affixed my 40 signature, in the presence of two witnesses.

FRANK D. POWELL.
